Henry Berger

HENRY BERGER, OF NEW YORK, N. Y.

Design No. 3,367, dated February 16, 1869.

DESIGN FOR A CENTRE-PIECE.

The Schedule referred to in these Letters Patent and making part of the same.

To all whom it may concern:

Be it known that I, HENRY BERGER, of the city, county, and State of New York, have invented a new and original Design for Centre-Pieces; and I do hereby declare the following to be a full, clear, and exact description thereof, which will enable those skilled in the art to make and use the same, reference being had to the accompanying drawing, forming part of this specification, which drawing consists of only one figure, showing my new and original design for centre-pieces.

Near the circumference of my centre-piece is an annular space, ornamented with foliage and shell-work, and within such annular space the surface of the centre-

piece is ornamented with leaf-like figures, which radiate from the central part of the design.

What I claim as new, and desire to secure by Letters Patent, is—

The design for centre-pieces, as above shown and described.

This specification signed by me, this 12th day of January, 1869.

HENRY BERGER.
